UNITED STATES PATENT OFFICE.

ERNEST A. SMITH, OF BARRY, IOWA.

BELT TOOL.

Application filed January 13, 1925. Serial No. 2,187.

To all whom it may concern:

Be it known that I, ERNEST A. SMITH, a citizen of the United States, residing at Barry, in the county of Guthrie and State of Iowa, have invented new and useful Improvements in Belt Tools, of which the following is a specification.

This invention comprehends the provision of a tool designed for association with a belt pulley to facilitate the application of a belt thereto, the tool being susceptible of adjustment to accommodate itself to pulleys of different widths and diameters.

The nature and advantages of the invention will be better understood when the following detail description is read in connection with the accompanying drawings, the invention residing in the combination, construction and arrangement of parts as claimed.

In the drawings forming part of this application, like numerals of reference indicate similar parts in the several views and wherein:

25 Figure 1 is a view showing the manner of using the tool.

Figure 2 is a plan view of the tool showing it associated with a belt pulley for use.

30 Figure 3 is a view showing a portion of a belt pulley and one of the positions occupied by the tool while in use.

Figure 4 is a sectional view on line 4—4 of Figure 3.

35 Figure 5 is a sectional view on line 5—5 of Figure 3.

The tool forming the subject matter of my invention comprises a lever 10 which is slightly curved longitudinally as shown and which terminates to provide an offset extremity 11 which is arranged substantially 40 at a right-angle to the lever 10, this offset extremity has associated therewith the shank 12 of a hook-like element, the hook 13 being turned downwardly. Pivoted upon the lever

45 10 at a point between its ends is an angular-shaped element 14 which terminates at one end to provide an offset extremity 15 which is arranged in parallelism with the offset extremity 11 of the lever and projecting in 50 the same direction therewith, while the opposite end of this element is elongated and slotted as at 16, the slot receiving a headed element 17 carried by the lever. Secured to the offset extremity 15 of the angular-shaped element is an arm 18 which terminates 55 to provide a down turned hook 19 ar-

ranged adjacent the hook 13, the arm 18 projecting an appreciable distance beyond the side of the lever 10 upon which the element 14 is pivoted for a purpose to be 60 presently described. Secured to the underside of the arm 18 is an additional hook-like element 20 which is slotted as at 21 to receive an adjustable element 22 carried by the arm 18. Manifestly, the hook-like element 20 is adjustable longitudinally of the arm 18 toward and away from the hook 19 thereof so that the tool can be adjusted to accommodate pulleys of different widths.

In Figure 1, I have illustrated the position of the tool upon the pulley indicated at 24, the hooks 13 and 19 engaging one side of the pulley while the hook 20 is adjusted to engage the opposite side of the pulley as shown, the arm 18 being arranged transversely of the pulley and projecting an appreciable distance beyond one side thereof. By reason of the slot and pin connection 16 and 17 between the lever 10 and the angular-shaped element 14, it is apparent that the hooks 13 and 19 may also be adjusted relatively so that the tool may be associated with pulleys of different diameters.

With the device positioned upon the pulley in the manner illustrated in Figure 1, the belt to be applied is supported upon the arm 18 as shown. It is of course to be understood that this belt is first applied to one of a pair of pulleys, the opposite end of the belt being supported by the arm 18 which is carried by the secondary pulley element indicated at 24. The lever 10 is then grasped by the operator and is utilized to turn the pulley approximately a half a revolution, during which time one edge of the belt is pushed by the left hand of the operator over the adjacent edge of the pulley 24, it being understood that it is only necessary to slip a portion of the belt over the pulley initially, as the belt will position itself on the pulley subsequently during the operation of the machine of which the pulleys form a part. After the pulley has been turned approximately a half a revolution and the portion of the belt positioned upon the pulley as described, the tool occupies a position illustrated in Figure 3, wherein it is arranged between the lower and upper runs of the belt where it is readily accessible so that it can be easily removed from the pulley. The tool is very simple in construction and can be readily applied to or

removed from the pulley as the occasion requires, and its use makes it possible for one man to apply a reasonably tight belt to a pulley in a manner specified.

5 While it is believed that from the foregoing description the nature and advantages of the invention will be readily apparent, I desire to have it understood that I do not limit myself to what is herein shown and described, and that such changes may be resorted to when desired, as fall within the scope of what is claimed.

What I claim is:

- 15 1. A tool of the character described comprising a lever, a hook-like element secured to one end of the lever and projecting laterally therefrom, an arm arranged transversely of the lever and projecting beyond both sides thereof, said arms terminating to provide a hook arranged in juxtaposition to the first mentioned hook, means for associating the arm with the lever, and a hook-like element carried by the arm at a point in its length.
- 20 2. A tool of the character described comprising a lever, a hook-like element secured to one end of the lever and projecting laterally therefrom, an arm arranged transversely of the lever and associated therewith, said arm terminating to provide a hook arranged in juxtaposition to the first mentioned hook, and a hook-like element secured to the arm at a point in its length.

and adjustable longitudinally thereof for the purpose specified.

3. A tool of the character described comprising a lever slightly curved longitudinally and terminating to provide an offset extremity, a hook-like element carried by said extremity and projecting laterally from the lever, an arm arranged transversely of the lever and associated therewith, said arm terminating to provide a hook arranged in juxtaposition to the first mentioned hook and projecting from the lever in the same direction therewith, and a hook-like element carried by the arm and adjustable longitudinally thereof for the purpose specified.

4. A tool of the character described comprising an angular-shaped lever, a hook-like element carried by one end of the lever and projecting laterally therefrom, an angular-shaped element pivoted at a point between its ends on said lever, a slot and pin connection between the lever and one end of said element, an arm carried by said element and arranged transversely of the lever, said arm terminating to provide a hook arranged in juxtaposition to the first mentioned hook, and a hook-like element carried by said arm and adjustable longitudinally thereof for the purpose specified.

In testimony whereof I affix my signature.

ERNEST A. SMITH.
